UNITED STATES PATENT OFFICE

AUGUSTO DINA, OF ELIZABETH, NEW JERSEY, ASSIGNOR TO INTERNATIONAL PROJECTOR CORPORATION, OF NEW YORK, N. Y., A CORPORATION OF DELAWARE

CONSTRUCTION OF PILOT LAMPS FOR MOTION PICTURE APPARATUS

Application filed July 23, 1931. Serial No. 552,679.

This invention relates to new and useful improvements in mountings for pilot lamps on motion picture apparatus, preferably projectors.

5 **5** An object of the invention is to provide a simple, economical, durable, self-contained, efficient pilot lamp unit which can be readily attached to and detached from the apparatus without involving any material alteration in 10 the construction of the apparatus, and without seriously interfering with the operation of the machine.

A further object is to provide a unit in 15 which the lamp is efficiently protected from injury while permitting the light from the lamp to properly fall on the film for the purpose of projection.

A still further object is to provide a unit in which the parts are so constructed and 20 related that the lamp guard or casing can be instantly removed from or attached to the unit and is provided with means whereby it is always accurately supported on the unit when attached thereto.

25 Yet a further object is to provide a unit the parts of which can be very quickly and easily disconnected for replacement and repair.

Further and more specific objects, features 30 and advantages will more clearly appear from a consideration of the specification hereinafter taken in connection with the accompanying drawings which form part of the specification and which illustrate a present preferred form of the invention.

Briefly the invention comprises a plate 35 adapted to be attached to a suitable supporting partition on the apparatus. This plate is provided with an outwardly extending 40 guide-plate from which a lamp guard or casing is slidably supported, preferably by means of cooperating tongues and grooves on the casing of the guide-plate. Preferably the spring pressed pins on the guide-plate frictionally engage the casing in order to retain it in position. The casing is also provided with a stop member which limits and advances its operative position when slid onto the guide-plate. The guide-plate is 45 preferably provided with an upstanding

flange acting as a support for a switch. The pilot lamp is mounted on a base suitably attached to the main plate and extending into the casing. Adjacent the filament of the lamp the casing is provided with a suitable aperture so angularly related to the lamp as to permit light therefrom to fall on an adjacent film aperture to permit the ready registration of the film with the aperture.

55 The present preferred form of the invention is illustrated in the drawings, of which:

Fig. 1 is an end elevation of the unit mounted on the machine;

Fig. 2 is a vertical section taken on the line 2—2 of Fig. 4;

Fig. 3 is a side elevation of the device; and

Fig. 4 is a vertical longitudinal section 70 taken on the line 4—4 of Fig. 2.

As illustrated in the drawings the present preferred form of the invention is especially applicable to motion picture apparatus, such as projectors provided with a film gate 75 10 adjacent which the film 11 is adapted to pass. As shown in the drawings on the opposite side of the gate 10 is disposed a tapered guard casing 12 attached to one face of a shutter casing 13. The apparatus 80 is provided with a vertical mechanism supporting partition 14 and it is to this partition that the tapered funnel or casing 12 of the unit comprising the invention, is attached.

85 This unit preferably comprises a main supporting plate 15 disposed vertically against the partition 14 by means of screws 16. Extending outwardly from this main support 15 is a horizontal guiding and supporting plate 17, the lower face of which is provided with a groove 18 in which a rib 19 is adapted to slide. This rib is disposed on the upper face of a lamp guard casing 20 which is open at its inner end and closed at its outer end. On its outer end it is provided with an upstanding stop flange 21 adapted to abut the outer end of the guide-plate 17 when the casing 20 reaches its operative position. The guide-plate 17 has 90 95 100

spaced apertures therein in which are mounted pins 22 and 23 having heads 24 and 25 to prevent their passing entirely through the aperture. These pins are 5 pressed into the aperture by means of arms 26 and 27 preferably formed in one piece and held in position by means of screws 28 fastened to the guide-plate 17. These pins 22 and 23 frictionally bear on the upper surface of the tongue or rib 19 to hold 10 it in position. The guard casing 20 is provided with a light opening 29 on the lower face thereof just above the tapered funnel 12 which is also provided with an opening 30. 15 These openings are so related that the light from the pilot lamp 31 projecting into the casing 20 will fall diagonally downward onto the aperture 32 in the film gate and illuminate the film, enabling the operator 20 to efficiently and easily register his film properly.

This lamp 31 is mounted in a socket 32 disposed on a suitable base 33 fastened by screws 34 to the main supporting plate 15. 25 The guide-plate 15 on its outer end is also provided with an upstanding flange 34 having a bore 35 in which is suitably mounted an electrical switch element 36 from which an operating handle 37 projects. 30 The switch and the lamp are connected by suitable wiring such as 38 and 39 with desired circuits so that the lamp can be illuminated or extinguished by the operator moving the handle 37 of the switch. Preferably this handle is disposed on the outer end of the unit so as to be readily accessible to the hand of the operator. Since the guard casing 20 is held in operative position merely by the frictional action of the 35 pins 22 and 23 it is merely necessary for the operator to grasp the casing 20 in his hand and pull it outwardly thus slipping the tongue 19 out of the groove 18 and enabling the lamp to be inspected, removed, 40 or replaced. The lamp unit itself can be removed by unscrewing the base 33 from the plate 15. The entire unit can be readily removed by removing the screws 16 thus enabling the plate 15 and the entire unit 45 being dismounted from the partition 14.

It will readily be noted that the device is simple, durable, economical and efficient and practically self-contained; the various parts can be readily assembled and disassembled; 55 the lamp can be readily inspected, replaced or repaired; and the device is disposed in a convenient position adjacent the film gate and it is readily accessible to the hand of the operator; and the whole unit when assembled can, in a few minutes, be applied to and removed from the machine without in any material way affecting the arrangement and operation of the machine.

While the invention has been described in 60 detail and with respect to a present pre-

ferred form thereof it is not to be limited to such details and forms since many changes and modifications may be made in the invention without departing from the spirit and scope of the invention in its broadest aspects. Hence it is desired to cover any and all forms and modifications of the invention which may come within the language or scope of any one or more of the appended claims. 75

What is claimed, is:

1. A pilot light unit for motion picture projectors which comprises a supporting plate, a guide-plate extending therefrom, and substantially at right angles thereto, a pilot lamp mounted on the supporting plate and extending therefrom substantially parallel to the guide plate, a guard casing for the lamp and a cooperating tongue and groove on the casing and the guide-plate 80 permitting the slidable movement of the casing on the guide-plate. 85

2. A pilot lamp unit for motion picture projectors which comprises a supporting plate, a guide-plate extending therefrom and substantially at right angles thereto, and having a groove therein, a lamp casing adapted to be slidably disposed on the guide plate substantially parallel thereto, a tongue in the lamp casing sliding in said groove, and resilient means on the guide-plate 90 engaging the casing to retain it in operative position thereon. 95

3. A pilot lamp unit for motion picture projectors which comprises a supporting plate, a guide-plate extending substantially at right angles therefrom and having a groove therein, a lamp casing adapted to be slidably disposed on the guide plate in a direction parallel thereto, a tongue in the lamp casing sliding in said groove, resilient means on the guide-plate engaging the casing to retain it in operative position thereon, said casing having a stop flange engaging the guide-plate when the casing is in operative position to define said position. 100 105

4. A pilot lamp unit for motion picture projectors which comprises a supporting plate and a guide-plate extending substantially at right angles therefrom and having a groove therein, a lamp casing adapted to be slidably disposed on said guide plate in a direction parallel thereto, a rib on said casing 110 slidable in said groove, pins on the guide-plate extending through apertures therein to frictionally contact with said rib and spring means on the guide-plate engaging said pins to force them into frictional contact with said rib. 115 120

5. A pilot lamp unit for motion picture projectors which comprises a supporting plate and a guide-plate extending substantially at right angles therefrom and having a groove therein, a lamp casing adapted to 125 be disposed slidably on said guide plate in 130

a direction parallel thereto, a rib on said casing slidable in said groove, pins on the guide-plate extending through apertures therein to frictionally contact with said rib and spring means on the guide-plate engaging said pins to force them into frictional contact with said rib, said casing having an upturned flange on its outer end to limit its inward movement on said guide-plate.

5 6. A pilot lamp unit for motion picture projectors which comprises a vertical supporting plate, a horizontal extending guide-plate, a lamp fastened to the supporting plate and extending horizontally beneath the guide-plate, a casing around said lamp and slidably mounted on said guide-plate, said guide-plate having on its outer end an upturned flange and a switch element mounted on said flange, said casing having 15 an upturned flange on its outer end to limit its inward movement on the guide plate.

20 In testimony whereof I have hereunto set my hand.

AUGUSTO DINA.
